A. R. BOLES.
VIOLIN CHIN REST.
APPLICATION FILED OCT. 11, 1916.

1,225,566.

Patented May 8, 1917.

UNITED STATES PATENT OFFICE.

ARTHUR R. BOLES, OF INDIANAPOLIS, INDIANA.

VOLIN CHIN-REST.

1,225,566.

Specification of Letters Patent.

Patented May 8, 1917.

Application filed October 11, 1916. Serial No. 125,081.

To all whom it may concern:

Be it known that I, ARTHUR R. BOLES, a citizen of the United States, residing at Indianapolis, in the county of Marion and State of Indiana, have invented certain new and useful Improvements in Violin Chin-Rests, of which the following is a specification.

This invention relates to violin chin rests and has as its object to provide a chin rest which may be readily and quickly applied to and removed from the body of a violin and which after application may be adjusted so as to position the chin plate at a greater or less distance above the violin body as the musician may find desirable. Incidentally, the invention aims to so mount the chin plate that the same may be vertically adjusted with relation to the body of the violin without the necessity of loosening and tightening set screws, nuts, or other similar elements, and likewise without the necessity of employing tools of any sort.

Another aim of the invention is to provide in connection with the fixed jaw of the clamping device for attaching the chin rest, a novel form of pad which will serve to prevent the said jaw marring the finish of the violin body and will also serve as a cushion when the instrument is placed against the shoulder, thereby eliminating any likelihood of any discomfiture being caused the musician and also insuring against slipping of the instrument.

35 In the accompanying drawings,

Figure 1 is a perspective view of the chin rest embodying the present invention;

Fig. 2 is a vertical longitudinal sectional view therethrough;

40 Fig. 3 is a perspective view of the lower clamping jaw;

Fig. 4 is a perspective view of the supporting posts for the chin plate;

Fig. 5 is a horizontal sectional view taken 45 substantially on the line 5—5 of Fig. 1.

The lower or fixed clamping jaw of the device comprises a jaw plate 1 which is preferably slightly arcuate in form so as to conform in a general way to the curvature 50 of the body of the instrument to which the rest is to be applied and at its outer edge the said jaw plate is provided with an up-standing shank 2 which is preferably slightly bowed or curved from end to end, 55 as clearly shown in Fig. 3 of the drawings and for a purpose which will be presently

explained. The said jaw plate 1 is further provided at each end of its said edge with an up-standing stem 3, the upper portion of which is threaded, as indicated by the numeral 4. The other clamping jaw of the device comprises a jaw plate, indicated by the numeral 5 and this jaw plate is provided at one edge and at or adjacent each end with a threaded stem 6, the said stems 65 extending downwardly with their ends opposing the ends of the stems 3 when the jaws are assembled. The jaw plate 5 is provided at its said edge with a downwardly extending shank 7 and this shank is provided at each vertical edge with a rearwardly extending flange 8, the edge portions of which flanges are turned inwardly, as at 9, so as to form a guide for the longitudinal edges of the shank 2 of the fixed jaw, it 70 being understood that the shanks of the said jaws are in this manner slidably connected. Sleeve nuts 10 are threaded onto the opposing ends of the stems 3 and 6 of the two jaws and it will be understood that 75 by rotating these stems the jaw 5 will be adjusted toward or away from the jaw 1 and, consequently, when the device has been disposed in proper position against the body of a violin the sleeve nuts 10 may be rotated 80 for the purpose of moving the jaw 5 downwardly into clamping engagement with the upper side of the said body, the jaw plate 1 engaging the underside of the said body.

The chin plate is indicated by the numeral 11 and may be of any ordinary or special form as desired and this plate is supported by a post, indicated by the numeral 12, which post has its upper end turned forwardly substantially at right angles as at 95 13, and secured by means of a screw 14 to the underside of the chin plate 11 at the rear edge thereof. The post 12 is preferably reinforced by a rib formed therein and extending longitudinally thereof, this rib 100 being indicated by the numeral 15. As stated, the shank 2 of the relatively fixed jaw is bowed or curved from end to end and when the shank is slidably fitted into the channeled shank 7 of the adjustable jaw the 105 tendency will be for the said shank 2 to bulge rearwardly toward the inturned edges 9 of the flanges 8. The post 12 is assembled with the clamping device comprising the said jaws and their shanks, by slidably fitting the post into the channeled shank 7 110 rearwardly of the shank 2, the vertical edge

portions of the post 12 slidably fitting behind the edge portions 9 of the flanges 8 in the manner clearly shown in Fig. 5 of the drawings and the post being held with its 5 said edges frictionally engaging the said edge portions of the flanges by reason of the resiliency of the shank 2 and the fact that the said shank is bowed so as to bear rearwardly against the forwardly presented side 10 of the post 12. It will now be understood that after the clamping device has been assembled with the violin body and the sleeve nuts 10 have been adjusted to clamp the said device to the body, the chin plate may 15 be adjusted vertically either in an upward or downward direction without disturbing the said clamping device. In order that the post 12 may be supported at various elevations one of the edge portions 9 is formed 20 with a series of rack teeth, indicated by the numeral 16 and a pawl 17 is pivoted, as at 18, upon the rear side of the post 12 near the lower end thereof and has a tooth, indicated by the numeral 19 which tooth is de- 25 signed to coöperate with the teeth 16 in the manner clearly shown in Fig. 1 of the drawings for the purpose stated.

As before stated, there is provided in connection with the chin rest, a pad or cushion 30 which is applied to the lower or fixed jaw of the clamping device and the said cushion, which is indicated by the numeral 20, may be formed in any suitable manner and is provided with a filling 21 of any suitable 35 cushioning material. In its upper side the cushion 20 is formed with a pocket which is indicated by the numeral 22 and which pocket is designed to receive the jaw plate 1 in the manner clearly shown in Fig. 2 of 40 the drawings. Referring to this figure and to Fig. 1 it will be observed that the upper side of the cushion 20 covers the upper surface of the jaw plate 1 and that, conse- 45 quently, when the clamping device has been secured in place the jaw plate will not mar the finish of the instrument. It will, fur- 50 thermore, be understood that the cushion 20 serves not only the function of a cushion but also as a covering for the jaw plate 1.

From the foregoing description of the in-

vention it will be seen that there is provided a violin chin rest which may be readily and quickly applied to and removed from a violin body and which is so constructed that the chin plate may be raised 55 or lowered without in any way disturbing the clamping device and without the necessity of employing tools of any kind or tightening or loosening the set screws or set nuts. It will further be apparent that the chin 60 rest proper, or more specifically the chin plate, together with its supporting post, may be bodily removed from the clamping device and that, therefore, the clamping device may remain upon the instrument after 65 being once applied, it being a simple matter to insert the post 12 into the channeled shank 7 and properly adjust the same when the instrument is to be played.

Having thus described the invention, what 70 is claimed as new is:

1. In a violin chin rest, attaching means embodying clamping jaw members, one of said members being provided with a channeled guide and the other member having 75 a resilient bowed shank slidably fitting within the guide, means for relatively adjusting the members, a chin plate, and a supporting post for the plate slidably fitting the said channeled guide, the said bowed 80 shank bearing frictionally against the said post.

2. In a violin chin rest, attaching means embodying clamping jaw members, means for relatively adjusting the members, one 85 of said members having a channeled guide, the side walls of the channel having inwardly extending flanges and the edge of one flange being formed with rack teeth, the other member having a bowed shank fitting 90 within the channeled guide with its bowed side presented toward the said flanges, a chin plate, a supporting post for the plate slidably fitted within the channeled guide between the inner sides of the said flanges 95 and the said bowed shank and frictionally engaged by the said shank, and a pawl upon the shank coacting with the said rack teeth.

In testimony whereof I affix my signature.

ARTHUR R. BOLES. [L.S.]
